UNITED STATES PATENT OFFICE.

FRANK D. LEWIS, OF DENVER, COLORADO.

ROTARY CENTRIFUGAL MINERAL HYDRO-EXTRACTOR OF THE HORIZONTAL TYPE.

Application filed May 9, 1925. Serial No. 29,151.

My invention relates to a rotary centrifugal mineral hydro extractor of the horizontal type.

The primary object of the invention is to provide an apparatus comprising a series of spaced concentrating cylinders which are open at one end and which lie one within another and are connected to rotate in unison, said cylinders being inclosed in and bolted to a cylindrical housing having hollow axial trunnions which are mounted in bearings and which act respectively to supply screened placer ground or ore pulp to the cylinders which, owing to the centrifugal action of their fast rotary movement, act to extract the gold and the mineral concentrates therein, and to discharge the tailings therefrom.

Further, to provide a rotary centrifugal mineral concentrating and placer or other free gold amalgamating apparatus comprising a horizontally disposed cylindrical housing having heads provided with hollow trunnions which are supported in bearings, said housing inclosing a series of spaced cylinders which are open at one end and which lie one within another, the closed ends of the cylinders being bolted to the heads of the housing in alternate order, the inner faces of said cylinders being provided with annular grooves, the innermost cylinder being continuously supplied with ore pulp through one of said hollow trunnions, said pulp being forced by centrifugal action from cylinder to cylinder, said cylinders being also supplied with quicksilver which fills the grooves therein, under centrifugal action, the material, as it is forced through the cylinder being subjected to both a concentrating and an amalgamating treatment, adjustable means being provided for separating the concentrates from the tailings at the discharge end of the housing, the tailings being discharged through the other hollow trunnion.

Further, to provide an apparatus of this character, having adjustable means for defining a concentrates discharge outlet and for regulating the flow of the concentrates through said outlet, adjustable means for congesting the flow of tailings to the tail-

ings discharge and rotary means for retarding the tailings outflow. These, and other objects to be hereinafter set forth, are accomplished by the mechanism illustrated in the accompanying drawings, in which—

Figure 1 is a side elevation of the improved centrifugal mineral hydro extractor.

Figure 2 is a vertical longitudinal sectional view of the same.

Figure 3 is a vertical transverse sectional view on the line 3—3 of Figure 2.

Figure 4 is a view of the discharge end of the machine, the impeller being omitted for clearer illustration, but shown in dotted lines.

Figure 5 is a front end view of the innermost concentrating cylinder.

Figure 6 is a horizontal sectional view of a portion of the same.

Figure 7 is an end view of the second concentrating cylinder.

Figure 8 is a horizontal sectional view of a portion of the same.

Figure 9 is an end view of the third concentrating cylinder.

Figure 10 is a horizontal section of a portion of the same.

Figure 11 is an end view of the fourth or outermost concentrating cylinder.

Figure 12 is a horizontal sectional view of a portion of the same.

Figures 13 and 14 are front and rear views respectively, of an impeller that is secured upon the front end of the first or innermost cylinder.

Figure 15 is a front end view of a half part of the concentrates discharge ring which lies over the discharge end of the shell or housing which encloses the concentrating cylinders.

Figure 16 is a sectional view of the same.

Figure 17 is a sectional view of an adjustable ring which acts in conjunction with the concentrates discharge ring for controlling the discharge of the concentrates.

Figure 18 is a front view of a half part of the ring shown in Figure 17.

Figure 19 is a front view of an adjustable ring for congesting the outflow of material in the passage leading to the tailings discharge outlet.

Figure 20 is a sectional view of the same.

Figure 21 is a vertical transverse sectional view of the impeller at the discharge end of the tailings outlet passage.

Figure 22 is a front view of the tailings retarding disk which is bolted upon the rear end of the outermost concentrating cylinder.

Figure 23 is a sectional view showing one way of securing the ends of the two-part tubular concentrates-receiving ring.

10 Figure 24 is a similar view showing a different way of securing the ends of said ring, and,

Figure 25 is a detail sectional view on the line 25—25 of Figure 4.

15 Similar reference letters and numbers refer to similar parts throughout the drawings.

Referring to the accompanying drawings:

20 The numeral 1 designates the bed plate of the apparatus, which is provided with narrow depending side and end portions which terminate in a flange 2, which rests upon the foundation or floor, the flange being provided with apertured lugs 3 for the reception of bolts or lag screws by which the bed plate is secured to the floor. Upon the opposite end portions of the bed plate are formed raised portions or bosses 4 to which are bolted standards 5 and 6, having roller bearings 7, in which are mounted hollow shafts or trunnions 8 and 9, respectively, which are rigidly mounted in the hubs 10 and 11, which are formed on caps or heads 12 and 13 respectively, which are bolted upon the ends of a cylindrical casing 14 which will hereinafter be more particularly referred to. The hollow trunnion 8 extends beyond the standard 5 and has rigidly mounted thereon a driven pulley 15, which is adapted to be belted to a driving pulley, and an idle pulley 16 is loosely mounted thereon adjoining the pulley 15. A collar 17 surrounds the trunnion 8 between the hub of the idle pulley and the standard 5, and a collar 18 is secured on the outer end portion of the said trunnion by a set screw 19, and these collars prevent endwise movement of the pulleys on the trunnion.

50 The outer portion of the trunnion 8 is counterbored for a suitable distance, and this counterbore is again counterbored to form a packing box 20, the outer portion of which is threaded to receive a packing gland 21, and a tube 22, of the diameter of the first counterbore, is inserted in the trunnion and abuts against the shoulder 23 formed by the said first counterbore. The outer end of the tube 22 is threaded to receive a pipe—not shown—through which ore pulp (which is finely ground ore, and water) is supplied to the apparatus.

60 The inner face of the cap or head 12 is formed with a circular boss 24, which is concaved as shown at 25 in Figure 2, the

surface of the concavity being curved in the manner shown, and of a diminishing diameter which terminates in a hole of the same diameter as the bore of the trunnion 8, with which it registers.

70 A horizontally disposed concentrating and amalgamating cylinder A is supported in the casing 14, so that its head 26 abuts against the boss 24, and covers the concavity 25 therein, and this cylinder A is the first of a series of four similar cylinders which are also supported within the casing. The first and third of these cylinders are bolted to the head 12 of the casing in the following manner: The head 26 of the first cylinder A is inset from the adjacent end of the cylinder, and this end of the cylinder fits over the boss 24 and is formed with a flange 27 which is provided with a circular series of threaded holes 28, as clearly shown in Figures 5 and 6. This cylinder extends to within a short distance of the opposite casing head 13, and terminates in an annular introverted lip 29, the purpose of which will hereinafter appear. The flange 27 of this cylinder is spaced from the casing head 12, and between the flange 27 and the said head 12, fits an introverted flange 30, which is formed on the front end of the third cylinder C, which is concentric with the first cylinder and spaced therefrom.

80 The third cylinder C, is of the same length as the first cylinder and also terminates in an annular introverted lip 31. The flange 30 of the cylinder C is provided with a series of threaded holes 32, (see Figures 9 and 10) and cap bolts 33 are passed through holes in the head 12 and through the threaded holes in the flanges 27 and 30 of the cylinders A and C respectively, as clearly shown in Figure 2, thereby securing these cylinders to the head 12.

90 The head 26 of the cylinder A is formed with a boss 34^A, over which fits the open end of a spacing cylinder 34, which lies within the concentrating cylinder A, and extends slightly beyond the open end of the same and terminates in a closed end 35. Against this end 35, is placed the closed end 36, of the second concentrating cylinder B, which extends in between the cylinders A and C, and terminates in an annular introverted lip 37, which is spaced from the flange 27 of the cylinder A. The end 36 of the cylinder B is flanged as shown at 38 in Figures 2 and 8 and the flange is provided with a circular series of threaded bolt holes 39.

100 Against the end 36 of the cylinder B is placed the end 40 of the fourth concentrating cylinder D, which surrounds the third cylinder C and terminates near the casing head 12 in an annular introverted lip 41. The head ends of the cylinders B and D are provided with registering holes 42 and

42^A, respectively, the holes 42 being threaded, and cap bolts 43 are passed through these holes and also through threaded holes in the end 35 of the spacing cylinder 34, thus clamping the heads of these three cylinders together. The cap bolts 43 also clamp the circular base portion of a retarding element 44, against the head 40, of the cylinder D, this element being shown in Figures 2 and 10 22, its function being hereinafter set forth.

The retarding element 44, consists of a circular plate or disk having a beveled edge and is provided with integral blades 44^A, which extend at right angles to the disk, 15 and which act to retard the flow of material to the axial outlet in the trunnion 9.

The cylinders B and D, together with the spacing cylinder 34, are supported on the rear casing head 13, by a circular series of 20 bolts 45, which extend through the head 13, through the holes 43^A, in the head 40 of the cylinder D, and through the threaded holes 39 in the head 36 of the cylinder B.

A circular series of bolts 46 are screwed 25 through threaded holes in the front casing head 12 and into shallow holes in the front end or rim of the cylinder D, and these bolts support the front end of this cylinder, and hold it and the cylinder B, 30 which is bolted to it, in a true horizontal position.

The four cylinders are held against end-wise movement with respect to each other by a bolt 47, which is passed through registering axial holes 48, 49, and 50, respectively, of retarding element 44, and the cylinder heads 40 and 36 and through the head end 35, of the spacing cylinder 34, the end portion of this bolt being threaded and 40 screwed through a threaded hole in the end of the cylinder A. The end of the bolt 47 extends beyond the cylinder head 26 and screws into a threaded hole 51, in the hub of a circular impeller 52, and clamps the 45 same against the outer face of the said cylinder head 26. The impeller 52 is disposed within the concavity 25 of the casing head 12, and is formed with a series of curved wings 53 which extend from near 50 the center of the impeller to points slightly beyond its circumference, as shown in Figures 13 and 14.

There are preferably six of these curved wings 53, and their outer ends extend across one end of a corresponding number of inlet slots 54 which are formed in the cylinder head 26, through which the ore pulp passes to the interior of the cylinder A. The cylinders A, B, C, and D are each provided with a series of spaced annular grooves or channels 55, for a purpose to be later explained, the cylinder A having the greatest number of these grooves, eighteen being shown in the drawings, the cylinder B having ten,

while the cylinders C and D each have 65 twelve.

The casing 14 is provided centrally of its length and at diametrically opposite points with threaded holes 56 and 56^A, respectively, and each of the cylinders A, B, C and D, 70 is also provided with similar holes, all of said holes being aligned. A bolt 57 is screwed through one set of holes, and a bolt 58 is screwed through the other set of holes. These bolts not only serve as an additional 75 means of supporting the cylinders and maintaining them in parallel order, but when the apparatus is at a stand-still and the bolt 57 is uppermost, quick-silver may be supplied to each of the cylinders by removing the said bolt 57 and passing the quick-silver down through the hole in each cylinder in any suitable way; and by removing the bolt 58, the quicksilver can be drawn off from the cylinders when necessary. 80

A longitudinal channel 59 is formed in each cylinder, which intersects the annular grooves 55, and also the holes 58^A through which the bolt 58 is screwed, and the function of these channels is to receive the quicksilver from the annular grooves 55, and pass it to the outlet holes 58^A, in emptying the cylinders. The casing 14 is also formed with a similar channel 59, which intersects the hole 56^A, and the said casing forms a concentrating but not an amalgamating unit. The axial bolt 47 passes through a sleeve 47^A, which abuts at one 90 end against the head of the cylinder A, and at the other end against the head of the spacing cylinder 34. 95

The casing 14 has flanged ends 60 and 61, the head 12 being connected to the flange 60 by a circular series of bolts 12^A, while the head 13 is connected to the flange 61 by a circular series of bolts 13^A. 100

The rear end portion of the casing 14 is counterbored for a short distance, and a flat ring 62 is placed over this end of the casing and is provided with a circular projection or boss 63, which fits into the said counterbore. The opening through the ring 62 is of a slightly less diameter than the inside diameter of the casing, but it gradually increases in diameter to the rim of the boss 63, which is flush with the inner face of the casing, the wall of the opening being curved in cross section as shown at 64, (see Figure 16). 110

The ring 62, tapers in thickness toward its circumferential edge, and the ring is held in engagement with the flange 61 of the casing by four adjustment screws 65, which are screwed through the head 13 of the casing and against the said ring 62. The function of the screws 65 is to define an outlet space between the ring 62, and the head 13, 120 125

which may be increased or diminished, as may be found necessary by turning the screws either to the right or left, these screws being shown in Figures 4 and 25. 5 The inner face of the casing head 13 is formed with an annular recess 66 (see Figure 2) in which are seated two rings 67 and 68, the ring 68 fitting snugly within the ring 67, and the two rings fitting snugly 10 in the recess 66. The inner face of the ring 67 is beveled at its circumferential edge portion, as shown at 6^A, in Figure 17, and this beveled edge lies directly behind the marginal edge of the opening in the ring 62, 15 and is adjustable with respect to the said marginal edge, to define an outlet from the casing for the concentrates, as will be hereinafter more particularly referred to, and this ring is adjusted to vary the outlet space, 20 in the following manner:

Four bolts 69 are screwed through the head 13 and extend slightly beyond the bottom of the annular recess 66 in the said head. The ring 67 is provided with four 25 screw holes 70, which are countersunk at their front ends as shown at 71 to receive the heads of four screws 72.

The ring 67 abuts against the four bolts 69, and the screws 72 are passed through 30 the holes in the ring and screwed into threaded holes in the bolts 69; and thus, by screwing the bolts 69 either in or out, the ring 67 is correspondingly moved, and thereby either increases or diminishes the space between it and the ring 62, which space is the 35 outlet space for the concentrates.

As shown in Figure 2, the rings 67 and 68 are behind the head end of the cylinder D, but are spaced therefrom, and this space 40 forms the entrance to an axial outlet recess or chamber 73, in the casing head 13, which is of conical form, and the retarder 44, which is bolted to the end of the cylinder D, lies in this outlet, and is provided 45 with blades 44^A, which stand at right angles to the circular body of the retarder, are highest at their inner ends, and slope down toward their outer ends, where they merge into the face of the body 44, as shown in 50 Figure 2. The ring 68, is also an adjustable ring and is positioned at the entrance to the outlet chamber 73, in the head 13, and its function is to congest the outflowing material at this point, so that the concentrates 55 may be permitted to pass out between the rings 62 and 67, and are thus prevented from being carried into the outlet chamber 73, with the tailings.

The ring 68, is slidably mounted on the 60 eight bolts 45, which connect the cylinders B and D with the head 13, and it is adjusted by four bolts 74, which are screwed through the head 13 and are connected to the ring 68 by screws 75, which pass through the 65 ring and into threaded holes in the bolts 74, 70

in the same manner that the ring 67, is secured to the bolts 69. Thus, the ring 68 may be moved inward to contract the space leading to the outlet chamber 73, thereby causing a congestion of the outflowing material 75 by which the concentrates which constitute the heaviest particles of the material may be carried, by centrifugal action, through their proper outlet, while the lighter particles or tailings pass over the concentrates 75 and into the outlet chamber 73. A flat ring 76, is secured upon the circumferential edge of the rear flange 61, of the casing 14, and projects inward beyond the flange. A similar flat ring 77 is also secured upon the 80 circumferential edge of the casing head 13 and extends inward over the ring 76, but is separated from it by a slight space.

The inner edge portions of these two rings 85 project through an annular slot 78, in a stationary tubular ring 79, which surrounds the casing 14, adjacent its flange 61, and is held between two angle plates 80, by bolts 81, which pass through the plates and through the tubular ring, the horizontal 90 flanges of the angle plate 80 being bolted to the bed plate 1, this arrangement being clearly shown in Figures 2, 3 and 4.

The tubular ring is preferably divided into two semi-circular parts and the ends of 95 the two parts may be connected as shown in Figure 23, by short sections of tubing 82, which are inserted in the meeting ends of the ring sections so as to lie partly in each ring section, and which are secured by screws or rivets 83 to the said section; or the meeting ends of the ring sections may be flanged as shown in Figure 24, and the flanges connected by bolts 85. The tubular ring 79 100 constitutes a concentrates receiving and discharging ring, and a part of the ring, at its lowest point, is cut off on a horizontal line, as shown at 86, in Figures 2 and 3, to provide an outlet opening from the ring.

A trough 87 having an inclined bottom, 110 is placed between the angle plates 80 and directly beneath the opening in the ring, and this trough receives the concentrates from the ring and conveys them to a suitable receptacle—not shown.

The outlet chamber 73 in the head 13, tapers to a diameter corresponding to the bore of the hollow trunnion 9 which receives the coarse product or tailings from the said chamber and discharges it through its outer 120 end. The outer end of the trunnion 9 is threaded and the hub of a runner is screwed thereon. This runner comprises a pair of spaced parallel disks 88 which are united by four equidistant radial blades 89 which 125 extend from near the center of the disks to their circumferential edges. The advance sides of these blades are curved as shown and their inner ends are spaced one from another to provide outlet passages 90. The 130

hub of the runner has an axial hole 91, which forms communication between the hollow trunnion 9 and the space between the runner disks, the material passing 5 through said trunnion being drawn into the space between the runner disks and out through the passes 90 between the blades 89. The runner is enclosed in housing 92, which is the same character of housing as 10 that of the common type of centrifugal pump, and comprises duplicate members which are each formed with circular chambers, and with flanges 93 which are connected by bolts 94 to form a housing which 15 is of the outline shown in cross section in Figure 2, and in the dotted side view in Figure 4.

A short horizontally disposed lateral outlet pipe or nozzle 95, is formed at the lowest 20 point of the housing, and is preferably threaded at its end portion to connect with a pipe—not shown—which conveys the tailings away from the machine. The runner and its casing constitute an impeller which 25 acts to draw the tailings through the hollow trunnion and discharge them continuously through the outlet 95, the runner being of a diameter best calculated to meet particular requirements.

30 The impeller housing 92 is supported between and bolted to angle plates 96, the horizontal flanges of which are bolted to the bed plate 1.

In operation, the cylinders A, B, C and 35 D, are first supplied with quicksilver, and this is done by removing the bolt 57 and inserting the spout of a funnel through the opening 56, in the casing 14, and through the aligned openings in the several cylinders 40 until the innermost cylinder A is reached, the end portion of the funnel spout being outwardly curved, so that when the spout is inserted in the hole of one cylinder its outlet end will be beyond or on one side of 45 the hole in the next cylinder, and thus prevent any of the mercury supply for one cylinder from being poured into the next cylinder. The amount of quicksilver for each cylinder is previously determined, and 50 the introverted annular lips on the open ends of the cylinder are deep enough to confine the quicksilver in each cylinder until the apparatus is put in motion, and when the apparatus is running under the required number 55 of revolutions per minute, which is from two hundred and fifty to five hundred revolutions, the quicksilver, under centrifugal force, will fill the annular grooves in each cylinder, as well as the longitudinal grooves, 60 flush with the surface of the cylinder, and each ring of quicksilver will then constitute an amalgamating surface. The machine is started and placed ground, screened to small gravel and, the sands of the beds of rivers 65 and creeks, or the pulp from ore treating

70 mills, which is finely ground ore mixed with water, in the proportion of about nine parts of water and one part of ore, is then supplied through the tube 22 and hollow trunnion 8, to the chamber 25 in the head 12, 75 where it is carried by the blades of the impeller 52, and under centrifugal action, to the rim of the said chamber which is curved as shown and directs the pulp against the end of the innermost cylinder A. The pulp 80 passes through the slots 54 in the end of this cylinder, and into the cylinder where, under centrifugal action, it is forced against the wall of the said cylinder. The gold which is the heaviest substance in the ore, 85 will hug the surface of the cylinder, and as the material is pushed forward by the continuous incoming supply, the gold will come in contact with the quicksilver in the cylinder grooves, and will be caught thereby, and 90 the other elements in the pulp will automatically arrange themselves in the order of their specific gravities. Thus the ore is given both a concentrating and an amalgamating treatment as it passes over the surface 95 of the cylinder. The concentrated product less that part of the gold caught by the quicksilver, passes through the open end of cylinder A into cylinder B and undergoes the same action as in A, and from cylinder B it passes into cylinder C, and thence into cylinder D, whence it passes into the casing 14, where it receives a concentrating but not an amalgamating treatment. From the casing, the concentrates pass through the outlet space between the rings 62 and 67, the ring 68 being 100 adjusted to congest the outflow from the cylinders, so that the concentrates may pass through their proper opening and not be 105 carried out with the coarse product. From the opening between the rings 62 and 67, the concentrates pass into the space between the ring 62 and the casing head 13, and as the face of the ring 62 inclines with respect to the face of the head 13—see Figure 2—the space between them widens toward the flat rings and thus preventing clogging of the concentrates in the said space, and from this space the concentrates pass between the flat rings 76 and 77 to the tubular ring 79, and thence into the trough 87, which 110 conveys them to a suitable receptacle for further treatment.

The coarser product, or tailings, passes 115 into the chamber 73 in the head 13, but the blades 44^A on the retarder disk 44 in said chamber, retard the outflow of the tailings, thus enabling any heavy material therein to be thrown outward by centrifugal force and be carried out with the concentrates. The tailings pass into the hollow trunnion 9, and the blades 89 of the runner disks 88, create a suction through the said 120 trunnion by which the tailings are rapidly 125 130

and continuously drawn through the said trunnion and runner to the housing 92 and out through the discharge pipe of said housing. All 5 adjustments can be easily and quickly made and the roller bearings 7 enable the machine to be operated with only the minimum of friction, the bearings being lubricated by means of oil cups 97 which are screwed into the tops of the standards 10 5 and 6.

After any desired quantity of ore has been run through the apparatus, the cylinders may be flushed by running pure water through them while the apparatus is rotating; then it is brought to a standstill and bolt 58 is removed, and the mercury in each cylinder will run from the annular groove 55 into the longitudinal channels 59 and through the holes 58^a in said cylinders, and 20 out through the hole 56^a in the casing and into a receptacle. The gold is then separated from the mercury in the usual manner, as by forcing the mercury through chamois skin, and the mercury is reserved for further use.

Having described my invention, what I claim as new, and desire to secure by Letters Patent is:

1. In an apparatus of the character described, 30 a cylindrical casing, a series of spaced cylinders in said casing which are arranged one within another and connected to said casing, said cylinders being open at one end, the open end of one cylinder being next to the closed end of the surrounding cylinder, means defining an inlet to the innermost cylinder, adjustable means for defining an annular outlet space from said casing, means for defining an axially aligned outlet from said casing, and means for rotating said casing.

2. In an apparatus of the character described, 45 a rotatable cylindrical casing having an axial inlet at one end and an axial tailings outlet at its opposite end and adjustable means for defining an annular concentrates outlet space in said opposite end; a series of spaced cylinders in said casing which are open at one end and arranged one within another and connected to said casing, the open end of one cylinder being next to the closed end of the surrounding cylinder, a tubular ring surrounding said casing and having an annular slot and an outlet opening and means defining an annular passage connecting said annular outlet space and said slot.

3. In an apparatus of the character described, 60 a cylindrical casing having heads provided with hollow trunnions and bearings for said trunnions, said trunnions defining an inlet and an outlet to said casing, an adjustable ring in the outlet end of said casing for defining an annular outlet, a tubular ring surrounding said casing adjacent to

its outlet end and having an annular slot and an outlet opening, means defining an annular passage connecting said annular outlet and said annular slot, a series of spaced cylinders in said casing which are open at 70 one end and arranged one within another, their closed ends being connected in alternate order to the respective heads of said casing, the open end of one cylinder being spaced from the closed end of the surrounding cylinder, the casing inlet communicating with the innermost cylinder.

4. In apparatus of the character described, 75 a cylindrical casing having heads provided with hollow trunnions which provide an inlet and an outlet for said casing, and supporting bearings for said trunnions, a space being provided between the discharge end of the casing and the adjacent head, adjustable means for defining said space, an adjustable ring in said latter head which acts in conjunction with the end of the casing to define an annular outlet to said space, a stationary tubular ring surrounding said casing adjacent to its discharge end having an annular slot and an outlet opening and means defining an annular passage connecting said space and the annular slot in said ring; a series of spaced cylinders in said casing which are 90 open at one end and arranged one within another, their closed ends being connected in alternate order with the respective casing heads, each of said cylinders being provided internally with a series of annular grooves, and the innermost cylinder being connected with the casing inlet.

5. In an apparatus of the character described, 100 a cylindrical casing having heads provided with hollow trunnions which define an inlet and an outlet for said casing, and bearings for said trunnions, the head at the outlet end of the casing being spaced from said outlet end, and adjustable means for defining said space, a series of spaced cylinders in said casing which are closed at one end and arranged one within the other and connected in alternate order with the casing heads, a space being provided between the closed end of the outermost cylinder and the outlet head of the casing which communicates with the outlet through the adjacent trunnion, adjustable means in the head for contracting said space, an adjustable ring in said head which acts in conjunction with the end of the casing for defining an annular opening into the space between the end of the casing and the head, a stationary tubular ring surrounding the casing adjacent to its outlet end, provided with an annular slot, and with an outlet opening, flat rings arranged one within the other and connected respectively with the end of the casing and its head, said rings 110

projecting into the slot in said tubular ring 120 125 130

and defining a passage connecting the space between the casing and its head with the interior of the tubular ring, said casing inlet communicating with the interior of the 5 innermost cylinder.

6. In an apparatus of the character described, the combination with a cylindrical casing having heads provided with hollow trunnions constituting an inlet and an outlet 10 let to said casing, bearings for said trunnions and a series of spaced cylinders in said casing which are closed at one end and arranged one within another, their closed ends being secured in alternate order to the 15 casing heads, the innermost cylinder being connected with the inlet passage, said cylinders being provided with annular internal grooves, said innermost cylinder being adapted to receive a continuous supply of 20 ore pulp which is passed through the succeeding cylinders under centrifugal action, whereby the heavier particles or concentrates are separated from the tailings, means defining an annular outlet at the rear end of 25 said casing for the concentrates and an adjustable ring for contracting or enlarging said outlet, a passage being formed between the outermost cylinder head and the adjacent casing head which opens to the outlet 30 trunnion and adapted to receive the tailings, adjustable means for congesting the material entering said passage, a retarding element in said passage, said cylinders being adapted to receive quicksilver which fills 35 said grooves under centrifugal action, thereby providing amalgamating surfaces.
7. In a horizontally disposed centrifugal concentrating and amalgamating apparatus, the combination with a rotatable cylindrical casing of a series of spaced cylinders therein 40 which are open at one end and arranged one within another, the closed ends of said cylinders being secured to the ends of the casing in alternate order, each of said cylinders being provided with internal annular channels and their open ends terminating in introverted lips, said casing and cylinders having diametrically opposite aligned threaded holes constituting inlets and outlets 45 for quicksilver, and bolts which normally close said holes, means defining an axial inlet connecting with the innermost cylinder whereby ore pulp is continuously supplied to said cylinder and passes through the succeeding cylinders under centrifugal action, said cylinders being supplied with quicksilver which fills said channels whereby the ore is subjected to both a concentrating 55 and an amalgamating action, an annular concentrate outlet in the rear end of said casing and adjustable means for enlarging or contracting said outlet, means defining an axial outlet passage from said casing for the tailings, means for retarding 60

the outflow to said outlet and an impeller 65 at the end of said outlet.

8. In a horizontally disposed centrifugal concentrating and amalgamating apparatus, the combination with a rotatable casing having a flanged rear end; of a head secured 70 to said end but separated therefrom by a space and means for defining said space, an adjustable ring in said head which acts in conjunction with the end of said casing to define an outlet to said space, a tubular 75 stationary ring surrounding said casing adjacent its rear end and provided with an annular slot, a flat ring secured to the casing flange and projecting into said annular slot, a flat ring secured to the cylinder head 80 and surrounding the first flat ring but spaced therefrom and also extending into said slot, said rings defining an annular passage connecting the space between the casing flange and head with the interior of 85 the tubular ring, an axial outlet being formed in said head.

9. In a horizontally disposed centrifugal concentrating and amalgamating apparatus, the combination with a rotatable casing, of 90 a rear head secured thereto, but spaced therefrom, and having an axial outlet, a ring on the end of said casing having a slightly smaller opening than the bore of 95 said casing, a ring adjustably mounted in an annular recess in said head which acts in conjunction with the first ring to define an annular concentrates opening communicating with the space between the casing and its head, means for increasing or diminishing the space between the end of the casing and its head, a receiver and means defining a passage between said receiver and 100 said space.

10. In a horizontally disposed centrifugal concentrating and amalgamating apparatus, the combination with a rotatable casing, a series of spaced concentric ore concentrating cylinders therein, which are closed at 105 one end, and means defining an inlet to the innermost cylinder; of a rear head for said casing which is adjustably spaced therefrom and provided with an annular chamber which terminates in an axial outlet 110 passage, an annular concentrates outlet in the rear end of the casing communicating with the space between the casing and its head and means for contracting or enlarging 115 said outlet, a space being provided between the closed end of the outermost cylinder and said head, an adjustable ring in said head for contracting said space, a retarding element on the end of said cylinder which enters the annular chamber in the 120 said head, an impeller at the end of said outlet passage, a receiver and means defining a passage connecting said receiver with the space between the casing and its head. 125

11. In a horizontally disposed centrifugal concentrating and amalgamating apparatus, a rotatable cylindrical casing having heads provided with hollow trunnions which form respectively an inlet to and an outlet from said casing and bearings for said trunnions, spaced concentric cylinders in said casing which are closed at one end, the closed ends being connected to the casing heads in alternate order, said cylinders having annular internal channels, and introverted lips at their open ends, a spacing tube between the closed ends of the innermost cylinder and the second cylinder and an axial bolt 10 extending through the closed ends of said cylinders, said innermost cylinder having a circular series of inlet openings in its closed end, an impeller secured to said closed end by said axial bolt having blades leading to said openings whereby ore pulp passing through the inlet trunnion is carried into the first cylinder and through the succeeding cylinders under centrifugal action, an annular outlet in the rear end of the casing for the concentrates, and means for contracting or enlarging said outlet, a passage leading to the outlet trunnion, and means for contracting said passage.

12. In a horizontally disposed centrifugal concentrating and amalgamating apparatus, the combination with a cylindrical casing having a flanged rear end, a head secured to said flanged end but separated therefrom, by space bolts in said head which abut against the end of the casing to define said space and means defining an annular outlet from the casing to said space, of a stationary tubular ring which surrounds said casing adjacent said flange, and provided in one side with an annular slot, a flat ring secured to said flange, a flat ring secured to said head and surrounding the first flat ring but spaced therefrom, said flat ring extending into the annular slot in said tubular ring and defining a passage connecting said tubular ring and the space between the casing and its head, whereby material discharging from the casing into said space is conveyed to said tubular ring, said tubular ring having an outlet opening.

13. In a horizontally disposed centrifugal concentrating and amalgamating apparatus, the combination with a rotatable cylindrical casing having heads provided with hollow trunnions constituting an axial inlet and an axial outlet and concentric concentrating and amalgamating cylinders in said casing and rotatable therewith, the innermost cylinder having inlet openings communicating with said axial inlet, of an impeller on the end of said cylinder in conjunction with said openings, a retarding element on the end of the outermost cylinder at the entrance to said axial outlet, an adjustable ring in the rear casing head which acts in conjunction with

the end of the casing to define an annular outlet for the concentrates and an adjustable ring in the rear casing for contracting the entrance to the axial outlet.

14. In a horizontally disposed centrifugal concentrating and amalgamating apparatus, a rotatable casing having hollow axial trunnions constituting an inlet and an outlet, spaced concentric cylinders in said casing and movable therewith, the innermost cylinder communicating with the inlet trunnion and the outermost cylinder opening into said casing, a space being defined between the head of the outermost cylinder and the adjacent casing head which communicates with the axial outlet; an adjustable ring in the rear casing head which acts in conjunction with the adjacent rim of said casing to define an annular concentrates outlet from said casing and an adjustable ring within the first ring which acts in conjunction with the head of the outermost cylinder to contract the space communicating with the outlet trunnion.

15. In a horizontally disposed centrifugal concentrating and amalgamating apparatus, a cylinder open at one end, said open end terminating in an introverted lip, said cylinder having a series of internal annular channels and a longitudinal channel which intersects said annular channels, and diametrically opposite threaded holes, one of which is at the intersection of the longitudinal channel and one of the annular channels.

16. In a mineral hydro extractor, the combination of a base plate, standards provided with bearings; horizontal hollow shafts rotatably mounted in said bearings; a group of spaced concentrically arranged cylinders secured to each other and to said shafts, each of said cylinders except the outer one being provided on its inner face with spaced annular grooves; means for feeding pulp into and through one of said shafts and into the inner cylinder whence it passes through the cylinders in successive order to the outer cylinder; means for separating the concentrates from the gangue matter in the outer cylinder and for conveying it to a storage receptacle; the gangue matter being discharged through the other hollow shaft.

17. In a mineral hydro extractor, the combination with a base plate and bearing standards mounted thereon, hollow shafts rotatably mounted in said bearings and arranged to support a mineral hydro extractor between them, one of which hollow shafts forms the mineral pulp inlet to said extractor and the other the tailings discharge outlet from said extractor, said mineral hydro extractor comprising two oppositely positioned heads facing each other and secured to the inner ends of said hollow shafts and a cylindrical casing secured between said heads, a plurality of spaced amalgamating

cylindrical casings within said outer cylindrical casing, means for rotating said shafts and said mineral hydro extractor, and means for feeding mineral pulp into said hollow shaft and into and through said hollow discharge shaft, and means including a fixed tube surrounding said rotating outer casing,

a concentrates passageway being provided for receiving the concentrates from said amalgamating cylinders and said outer casing and discharging it into said fixed tube. 10

In testimony whereof I affix my signature.

FRANK D. LEWIS.
